The ornamental design of a footrest, as shown and described.

DESCRIPTION

FIG. 1 is an oblique view of a footrest on a chair, showing my new design;

FIG. 2 is a front elevation view thereof;

FIG. 3 is back elevation view thereof;

FIG. 4 is a side elevation view thereof;

FIG. 5 is a side elevation view thereof, showing the side that is opposite the side shown in FIG. 4; and,

FIG. 6 is a top plan view thereof.

The parts of the chair other than the footrest are shown in broken lines for illustration purposes only and form no part of the claimed design.

The characteristic feature of the design resides in the application of a part having the appearance of steering wheel to a footrest.
